UNITED STATES PATENT OFFICE.

ALBERT H. RAY, OF ASHLAND, MASSACHUSETTS.

PRINTING-MACHINE.

1,288,191.

Specification of Letters Patent. Patented Dec. 17, 1918.

Application filed January 7, 1916. Serial No. 70,872.

To all whom it may concern:

Be it known that I, ALBERT H. RAY, a citizen of the United States, residing in Ashland, in the county of Middlesex and 5 State of Massachusetts, have invented an Improvement in Printing-Machines, of which the following description, in connection with the accompanying drawings, is a specification, like characters on the drawings 10 representing like parts.

This invention relates to a printing machine of the character shown and described in U. S. Patent No. 1,104,829 granted to me July 28, 1914, in which a continuous strip or 15 web of paper or like material is intermittently fed between coöperating printing members, one of which is reciprocated with relation to the other.

The invention has for its object to provide 20 a superior machine of the character described, and one in which printers' ink may be supplied to the type, whereby a superior printing effect may be obtained with machines of the character specified.

25 To this end the machine is provided with means, as will be described, for enabling the reciprocating printing member to remain stationary in its withdrawn or inoperative position for a substantial length of time, to 30 permit an inking device to be moved over and into contact with the type.

Provision is also made for obtaining an even distribution of the ink on the inking device, as will be described.

35 The machine is further provided with a novel mechanism for feeding the paper strip or web, and with means for severing the printed section from the continuous web to form a printed tag or label.

40 Provision is also made for counting the number of tags or labels printed on the machine.

These and other features of this invention will be pointed out in the claims at the end 45 of this specification.

Figure 1 is a plan view of a printing machine embodying this invention.

Fig. 2, an end elevation of the machine shown in Fig. 1, looking toward the right.

50 Fig. 3, a detail in plan of the lever for operating the reciprocating printing member.

Fig. 4, a longitudinal section of the machine, taken on the line 4—4, Fig. 1.

Fig. 5, a section of the feed mechanism with the latter in its inoperative position. 55

Fig. 6, a rear side elevation of the machine shown in Fig. 1.

Fig. 7, a cross section on the line 7—7, Fig. 4.

Fig. 8, an inverted view of the reciprocating printing member. 60

Fig. 9, a detail in plan of a portion of the feed mechanism, and

Fig. 10, a detail in plan of a portion of the paper web or strip. 65

Referring to the drawings, *a* represents a continuous strip or web of paper or like material, which is preferably taken from a roll *b* and intermittently fed between a printing couple, by which it has printed upon it any desired characters according to the particular use to which the label or tag is to be put, which latter is formed by severing a printed section of the web from the continuous or unprinted strip or web. 70

The printing couple comprises a stationary member 10 and a movable member 12 (see Fig. 4) which is reciprocated with relation to the stationary member.

In the machine herein shown, the reciprocating printing member 12 is movable in a vertical plane toward and from the stationary member 10, which latter is suitably supported upon a cross-bar 13 of the base portion 14 of the framework of the machine, 80 and is preferably provided on its upper surface with a pad 15 of yielding material.

The reciprocating printing member 12, 85 may be of any suitable construction and comprises as herein shown a chase 16 for the type 17, the said chase being detachably secured to the head or lower end of a plunger 18, which is movable in a stationary cylinder 19 suitably attached to uprights 20, 21, erected upon the base 14 and forming part 90 of the framework of the machine. Provision is made for reciprocating the plunger 18, so that it may have a long stroke and enable it to be separated a substantial distance from the stationary member, for a 100 purpose as will be described, and also to enable the plunger to remain stationary in

its elevated or withdrawn position for a substantial length of time, for a purpose as will be described.

To this end, the plunger 18 is connected 5 by a link or rod 22 to the long arm of a lever 23 extended through the upright 20 and pivoted at 24 to lugs or ears 25 thereon, (see Figs. 2 and 3) and the opposite end of the lever is operatively connected with a 10 cam, preferably a path cam 26 in one face of a disk 27, mounted on a shaft 28 having bearings in the uprights 20, 21. The path cam 26 has extended into it a roller 29, which in the present instance is attached to 15 a bar or block 30, which slides in a guide 31 attached to the upright 20. The sliding bar or block 30 is connected with the short arm of the lever 23 by links 32.

By means of the lever 23, the movement 20 or stroke of the plunger 18 is lengthened, so that the type 17 are separated from the stationary printing member 10 a sufficient distance to permit of the passage between the printing members of a device for inking 25 the type, which device is preferably a roller 34 of substantial size, and the path cam 26 is suitably shaped to hold the type carrying member 12 stationary in its withdrawn position a substantially long time, 30 that is, a sufficient length of time to enable the inking roller to be passed under and in contact with the type, to supply the latter with regular printers' ink. The path cam 26 and lever 23 also serve to force the type 35 against the paper with increased power and thereby obtain a superior printing effect upon the paper.

It is preferred to employ a plurality of the inking rollers 34, and in the present instance, I have shown three such rollers, which are detachably secured to an endless carrier, herein shown as two parallel link chains 36, which are passed about sprocket wheels 37 on the cam shaft 28 and about 40 45 sprocket wheels 38, 39, on shafts 40, 41, journaled in the uprights 20, 21, near the lower end of the same and on opposite sides of the path of movement of the reciprocating printing member.

50 The shafts 40, 41 are arranged in a substantially horizontal plane, so that the endless carrier has imparted to it a substantially triangular form with the base of the triangle below the level of the reciprocating printing member 12 when the latter is in its elevated or inoperative position shown in Fig. 4. As a result, the inking roller 34 is moved in a substantially horizontal path on its passage beneath the reciprocating printing member 12, and makes contact with the type carried by said member, and thereby applies the ink to said type.

It is preferred to apply fresh ink after each printing stroke of the reciprocating

printing member 12, and to this end, a plurality of inking rollers 34 are employed, herein shown as three in number, which are arranged equi-distant apart on the endless carrier, so that at each revolution of the cam shaft 28 the endless carrier will be 65 70 moved a sufficient distance in its travel to carry one of the ink rollers 34 from one side of the path of reciprocation of the printing member to the other side of said path and cause said roller to engage and ink the type. 75

Provision is made to insure good contact of the ink roller with the type and counteract slackness in the horizontal portion of the endless carrier, and to this end, idler sprocket wheels 43 are located below the 80 path of movement of the endless carrier to engage the underside of the same substantially in the longitudinal center of the reciprocating printing member (see Fig. 4). Provision is also made for insuring that the 85 ink be evenly applied to all the type, by providing for an even distribution of the ink on the circumference of the inking roller. This result is accomplished in the present instance, by means of a distributing device in 90 the form of a disk 50 (see Fig. 2), which is pivoted at 51 to a support, herein shown as a sheet metal strip 52, which is bent to fit over upon and be supported by the bearings for the cam shaft 28 (see Fig. 4). 95

The disk 50 is of a diameter substantially equal to the length of the inking rollers 34, and is provided on its circumference with teeth 53, which are designed to be engaged by a series of pawls, lugs or projections 55, 100 one for each inking roller 34, which pawls are attached to one of the link chains 36 and are located on said chain so as to engage a tooth on the disk 50 and rotate the latter while an inking roller 34 is disengaged from 105 said disk.

The rotation of the disk causes any surplus of ink at one end or part of the roller to be distributed throughout the length of said roller, thus obtaining an even coating 110 of ink on the roller.

In this manner a superior inking of the type is insured, with the result that uniformity in color on the web *a* is obtained.

Provision is made for feeding the web or 115 strip *a* to the printing mechanism, and to this end there is provided a novel feed mechanism which has provision for engaging the paper web at a plurality of points between the side edges of said web. The feed mechanism herein shown consists essentially of a plate 60 (see Figs. 4, 5, 7 and 9), having a plurality of pins or projections 61, which are arranged in rows lengthwise of the plate near the opposite sides of the same, and are 120 spaced apart a distance substantially equal to the width of a section of the web which is to be printed upon. The feed pins 61 are 125

designed to enter holes or openings 62 in the web between the sections to be printed upon, said sections being marked 63 in Fig. 10.

- The plate 60 is supported upon a carriage, 5 herein shown as a frame composed of side bars 64 connected by cross end bars 65 and a center bar 66 (see Figs. 9 and 10). The side bars 61 are movable in guideways 67 in the opposite side walls of the base 14. 10 The central bar 66 is provided with a lug or ear 68 to which one end of a connecting rod 69 is pivoted, the other end of said rod being pivotally connected to a crank pin 70 on a disk 71, which is fast on a shaft 72 supported by the base 14 and rotated as 15 will be described, so as to reciprocate the carriage with relation to the printing mechanism.

On the forward stroke of the feed carriage 20 toward the printing mechanism, the pins 61 are extended into the holes 62 in the web *a*, so as to carry the latter toward the printing mechanism a distance substantially equal to the width of one section 63 of the web.

25 To enter the pins 61 in the holes 62, the plate 60 is raised from its lowered position shown in Fig. 5 into that shown in Fig. 7, and this movement of the plate 60 is effected as herein shown by a cam 73 on a shaft 30 74, which is rotated as will be described.

The cam 73 acts on a bar 75 having at its opposite ends posts or rods 76, which are movable in hollow bosses 77 on the under side of the center bar 66 of the carriage, said 35 posts having the plate 60 secured to their upper ends as by screws 78.

The cam 73 is suitably shaped and timed so as to raise the plate 60 when the feed carriage 64, 65, is at the end of its stroke 40 away from the printing mechanism, and thereby raise the pins or projections 61 into the holes 62 in the web *a* and to keep said pins or projections in said holes while the shaft 72 is making a half turn in the direction indicated by the arrow 79, Fig. 4, thereby causing the paper web to be fed between the printing members and into position to be printed upon. At or near the end of the forward movement or stroke of the carriage

45 64, 65, the cam 73 allows the plate 60 to drop by gravity assisted by a spring 80, so as to withdraw the feed pins 61 from the holes 62 in the web, and when the feed pins have been withdrawn, the carriage is moved 50 backward or away from the printing mechanism and the pins 61 are properly positioned below and in line with a new set of holes 62 in the web. The shafts 72, 74 may be driven from the cam shaft 28 by a link chain 82 (see Fig. 6), which engages a sprocket wheel 83 on the shaft 28, a sprocket wheel 84 on the shaft 72 and a sprocket wheel 85 on the shaft 74.

The web or strip *a* is guided on its for-

ward movement by a guide plate 86 supported by the base 14, and provided with a channeled or depressed portion 87 (see Fig. 7), which is of a width substantially equal to the width of the web *a*, and the latter is retained in said depressed portion by a cover 70 88 which is hinged at 89 to one side of the base.

The printed section 63 of the web may be severed from the continuous or unprinted portion of said web, by a cutting mechanism, 75 which comprises as herein shown two stationary cutter bars 90, 91, spaced apart and secured to the base 14 (see Fig. 4), and a movable cutter 92 which is arranged to pass down between the stationary cutter bars. 80

The movable cutter 92 is shown as a blade or bar attached to a lever 93, which is pivoted at 94 (see Fig. 2), and has its short arm 95 connected by a link 96 (see Fig. 6), with a lever 97, which is connected by a link 85 98 with the slide bar 30, which carries the cam roller 29, so that the movable cutter 92 is operated at the proper time by the path cam 26 to sever the narrow strip 99 (see Fig. 10), in which the holes are formed and 90 which are located between adjacent sections 63 to be printed. The lever 97 is guided in its movement by a bracket 100 attached to the base 14.

The operation of the machine may be 95 briefly described as follows:—

The continuous strip or web *a* of paper provided with the spaced holes or openings 62, is taken from the roll *b* and placed in the channel 87 of the guide plate 86, so that 100 some of the holes 62 register with the feed pins 61 when the latter are elevated. After the paper web has been properly positioned as described, the shaft 28 is rotated, which 105 may and preferably will be effected by the operator, turning a suitable crank or handle 101, attached to the shaft 28 (see Fig. 1).

The shaft 28 constitutes the main or driving shaft for the machine, and at each rotation, the web *a* is fed forward between the 110 printing members and into position to have a section 63 of the web printed upon by the type 17. After the paper web has been fed forward as described, it remains stationary while the printing is being performed, which latter is effected by the type-carrying plunger 18 being moved downwardly by the lever 23 under the influence of the path cam 26. After a section 63 has been printed upon, the plunger is elevated, and one of the 115 inking rollers is carried between the printing members by the endless carrier and is engaged with the type to ink the same. The web is then fed forward and an unprinted section is brought into position to be printed, and the printed section is fed between the 120 stationary and movable cutters, and on the next printing stroke of the plunger 18, the 125

movable knife 92 is engaged with the portion 99 of the web between the printed section and the one being printed upon, and said portion is severed from the continuous strip 5 and from the printed section, thereby leaving the latter free from holes and in a finished condition.

The printed section forms a label or tag and may drop onto the bench or into a suitable receptacle not shown. As the endless carrier is moved in the direction of the arrow 103 in Fig. 4, each inking roller is engaged with the distributing disk 50, which is rotated more or less as described so as to 10 distribute the ink evenly over the roller. The ink may be applied to the roller by the operator after the said roller has passed from engagement with the type and before it reaches the distributor. 15

20 It may be preferred to count the number of labels or tags printed by the machine, and to this end the base 14 has secured to it a counting device 104 of known construction, which is operatively connected by a flexible shaft 105 with the cam shaft 74 of the feed mechanism, so that, each revolution of the cam shaft 74 will be indicated by the counting device. 25

30 In the present instance, the counting device is shown as provided with a rotatable pointer 106 movable over a dial 107, provided with graduations indicative of one hundred revolutions of the cam shaft 74.

35 It will be observed that the endless carrier for the ink rollers is continuously operated while the reciprocating printing member is intermittently operated and that both are operated from the same shaft.

40 I have herein shown one embodiment of the invention, but it is not desired to limit the invention to the particular construction herein shown.

Claims:

45 1. In a machine of the character described, in combination, a printing mechanism having printing members, a rotatable shaft, means actuated by said rotatable shaft for intermittently reciprocating one of said printing members and for holding it stationary for a substantial length of time in its withdrawn position, a device movable between said printing members for applying ink to said reciprocating member, an endless carrier for said inking device, means actuated by said rotatable shaft for continuously moving said endless carrier in one direction in a fixed path independently of said reciprocating member. 50

55 2. In a machine of the character described, in combination, a printing mechanism having members, one of which is reciprocated, a device movable between said printing members for applying ink to said reciprocating member, an endless carrier for said inking device, means for intermittently

reciprocating one of said printing members and for holding it stationary for a substantial length of time in its withdrawn position, means for moving said endless carrier continuously in a fixed path independently of the reciprocating member, an ink distributing device with which said inking device makes contact in its travel, and means carried by said endless carrier for moving said distributing device. 70

75 3. In a machine of the character described, in combination, a printing mechanism having a reciprocating member, a lever to which said member is connected, a sliding block, means connecting the sliding block with said lever, a rotatable shaft, a disk mounted on said shaft and having a path cam in one of its faces, and a projection on said sliding block extended into said path cam. 80

85 4. In a machine of the character described, in combination, a frame, a printing mechanism having members supported by said frame, means for reciprocating one of said members and for holding it stationary for a substantial length of time in its withdrawn position, an inking device movable between said printing members, a continuously movable endless carrier for said inking device mounted on said frame to move in a fixed path independently of said reciprocating printing member, a feed mechanism for feeding a web between said printing members, and an actuating device common to said endless carrier, feed mechanism and the reciprocating member of said printing mechanism. 90

95 5. In a machine of the character described, in combination, a frame, a printing mechanism having members, supported by said frame, means for reciprocating one of said members and for holding it stationary for a substantial length of time in its withdrawn position, an inking device movable between said printing members, an endless carrier for said inking device mounted on said frame to move in a fixed path independently of said reciprocating printing member, an ink distributing device with which the inking device cooperates, and means engaging the external surface of the endless carrier for insuring efficient contact of the inking device with said reciprocating printing member. 100

105 6. In a machine of the character described, in combination, a printing mechanism having members, one of which is reciprocated, a device movable between said printing members for applying ink to the reciprocating member, an endless carrier for said inking device, a reciprocating feed mechanism having a member movable substantially at right angles to its path of reciprocation to engage a web and feed it to the printing mechanism, a cam shaft pro- 110

vided with a cam to move said member of the feed mechanism, a rotatable counter-shaft to which said feed mechanism is connected to be reciprocated by rotation thereof, a rotatable shaft for driving said endless carrier, and means for operatively connecting said cam shaft and said counter shaft with the driving shaft for said endless carrier.

- 10 7. In a machine of the character described, in combination, a printing mechanism having a reciprocating member, mechanism for feeding a web or strip to said printing mechanism while the reciprocating printing member is in its withdrawn position, a cutting mechanism having a movable cutter to sever the printed portion of the web from the unprinted portion thereof, a rotatable cam to effect reciprocation of said reciprocating member and to hold it stationary for a substantial length of time in its withdrawn position, and means for operatively connecting said cam with said reciprocating member and with said movable cutter to cause said cam to operate said reciprocating member and movable cutter in unison.
- 20 8. In a machine of the character de-

scribed, in combination, a printing mechanism having coöperating printing members, one of which is reciprocated with relation to the other, an inking device movable between said printing members, an endless carrier for said inking device, a cam shaft provided with a path cam, a lever actuated by said path cam and connected with said reciprocating member, and means actuated by said cam shaft for moving said endless carrier.

9. In a printing machine of the character described, in combination, a printing mechanism having members, means for reciprocating one of said printing members and for holding it stationary for a substantial length of time in its withdrawn position, an inking device movable between said printing members, an endless carrier for said inking device, means for continuously moving said endless carrier in a fixed path independently of the reciprocating member, and means engaging the external surface of the endless carrier for taking up the slack therein.

In testimony whereof, I have signed my name to this specification.

ALBERT H. RAY.

Copies of this patent may be obtained for five cents each, by addressing the "Commissioner of Patents, Washington, D. C."
